DESIGN FOR LEATHER OR SIMILAR ARTICLE

Robert C. Krauss, Brooklyn, N. Y., assignor to
F. A. Ringler Co., New York, N. Y., a corporation of New York

Application April 29, 1944, Serial No. 113,418

Term of patent 3½ years

(Cl. D87—3)

To all whom it may concern:

Be it known that I, Robert C. Krauss, a citizen of the United States, residing at Brooklyn, New York, in the county of Kings and State of New York, have invented a new, original, and ornamental Design for Leather or Similar Article, of which the following is a specification, reference being had to the accompanying drawing, forming part thereof.

In the drawing

Fig. 1 is a plan view of a piece of leather showing my new design;

The design unit is contained between the dot and dash lines, which unit is repeated in regular succession as indicated by the extensions beyond the unit boundaries.

Fig. 2 is an enlarged sectional view taken on line 2—2 of Fig. 1.

I claim:

The ornamental design for leather or similar article, substantially as shown and described.

ROBERT C. KRAUSS.
